UNITED STATES PATENT OFFICE

CHALON E. BRIDWELL, OF DETROIT, MICHIGAN

BOAT

Application filed March 14, 1927. Serial No. 175,114.

My invention relates to a new and useful improvement in a boat, and particularly, the buoying portion thereof and the propelling portion.

5 It is an object of the present invention to provide a boat which may be constructed on a production basis and made from various sections to be joined together so that after the various sections have been assembled, the completed boat will be in condition for use.

Another object of the invention is the provision of a boat having a plurality of rotatable propelling members associated with buoying members so that a minimum resistance is offered when the boat is propelled through the water, thus increasing the efficiency of the propelling mechanism, and rendering the boat more efficient for travel.

Another object of the invention is the provision of a boat having a carrying portion which is normally elevated above the water line so that only the propelling buoying mechanism is in contact with the water.

Another object of the invention is the provision of a buoying mechanism for a boat having a plurality of compartments formed therein, sealed from each other so that damage to one of said compartments will not interfere with the functioning and operation 30 of the other compartments.

Another object of the invention is the arrangement and construction of a rotatable propelling mechanism of considerable length so arranged and constructed that its contact 35 with the water immediately places the water under pressure for propelling the vehicle forwardly.

Another object of the invention is the arrangement of a propelling mechanism for the 40 boat in which a rotatable member is provided with a propelling fin, the fin being so constructed that it engages enough cubic feet of water to permit the same to act as substantially a solid body, the weight of the water 45 engaged being much greater than the weight of the boat, so that the propelling of the boat is effected with very little disturbance of the water.

Another object of the invention is the provision of a buoying mechanism having a plu-

rality of communicating sections and provided with automatically operated valves, so that should one of the sections spring a leak, the other sections will automatically be closed from communication therewith.

Another object of the invention is the provision of a propelling mechanism whereby the buoying members will be reinforced at their centers.

Other objects will appear hereinafter.

The invention consists in the combination and arrangement of parts hereinafter described and claimed.

The invention will be best understood by a reference to the accompanying drawings which form a part of this specification and in which,

Fig. 1 is a top plan view of the invention applied to a boat with a part broken away and a part shown in section.

Fig. 2 is a side elevational view of the boat embodying the invention with a part broken away and a part shown in section.

Fig. 3 is a fragmentary vertical central sectional view of the forward part of a boat embodying the invention.

Fig. 4 is a sectional view taken on substantially line 4—4 of Fig. 3.

Fig. 5 is a sectional view taken on substantially line 5—5 of Fig. 1.

Fig. 6 is a sectional view taken on substantially line 6—6 of Fig. 1.

Fig. 7 is an enlarged central vertical sectional view of the controlling valve used in the invention.

Fig. 8 is a side elevational view of a modified form of propelling and buoying mechanism with a part broken away and a part shown in section.

Fig. 9 is a fragmentary side elevational view of the invention with a part broken away and a part shown in section.

Fig. 10 is a side elevational view of a modified form of the buoying member used in the invention.

Fig. 11 is a view taken on substantially line 11—11 of Fig. 8.

Fig. 12 is a top plan view of a further modified form of the invention with a part broken

away and illustrating the use of a differentia.

Fig. 13 is a fragmentary sectional view of one of the valves used in the invention.

5 In the drawings I have illustrated the invention applied to a boat having a body 17 to provide a space 18 for carrying purposes, this space 18 having the floors 19 and 20 separated at the center. If desired, the space 10 across the center may be closed with a suitable trap door so as to provide an uninterrupted deck.

The side 17 serves as a covering for the frame work of the boat, this frame work being reduced to a minimum, as it is intended to construct the boat as light as possible, and yet form it sufficiently durable for the purposes to which it is to be put.

Extending downwardly of the boat in 20 alignment with the passage between the floors 19 and 20 is a trough shaped member 21 to which is connected, depending therefrom, a substantially rectangular container 22, communication between the trough shaped member 21 and the container 22 being effected by the valve 23. This container 22 and the trough shaped member 21 extend rearwardly and forwardly from opposite sides of the center of the boat, the propelling mechanism being 30 located preferably at the center.

Extending longitudinally of the boat are arcuate shielding and reinforcing members 24 and 25, each of which, at the inner end, is secured to the trough shaped member 21 by 35 welding or in any other suitable manner, and each of which is angularly turned at its outer end to extend upwardly as at 26 and inwardly as at 27, the inner end 28 being angularly turned and secured to the side walls 17 by 40 welding or in any other suitable manner.

The angularly extended portion 27 is provided with the opening 29 closed by a suitable closure 30. On the outer surface of the portion 26 is an enlarged abutment member 45

31. At the prow and at the stern of the boat there is positioned a casting 32 which is provided with a plurality of compartments 33, each of which is covered with a cover 34, leaving the space 35 at the center open in the bottom, the construction being such as to provide at the stern and the bow, a sort of air cushion for preventing excessive rocking of the boat on a transverse axis. Projecting downwardly from the casting 32 at the forward end and supported thereby is a bearing 36, extending through which is a bolt 37 which is adapted to engage in the inwardly projecting boss 38 to afford a support for the forward section 39 of the buoying drum used 55 in the invention. This drum, as shown in the drawings, is made up of the forward section 39, intermediate sections 40—the number of these intermediate sections being dependent upon the size of the boat with which used—

60 and an end section 41. The sections illus-

trated in Fig. 3 are those located forwardly of the boat, and a similar set of sections would be located at the rearward part of the boat. The section 39 is secured to the section 40, and sealed therefrom, by a disc 42 having the flange 43 which is riveted or otherwise secured to the drum. This disc 42 is provided with a central opening 43' closed by the cover 44. Mounted on the cover 44, centrally thereof, is a valve 23 having at one end the socket 45 in which is slidably mounted the piston head 46, said piston head carrying the stem 47. Positioned upon the stem 47 in embracing relation is a spring 48 engaging at one end in a recess 49 formed in the piston 46, and at the other end in the recess 50 formed in the valve plug 23. The stem 47 projects into the passage 51 which communicates through the passage 52 with the compartment 40'. The passage 51 communicates through the 85 passage 53 formed in the plug 54 with the passage 55 formed in the plug 56 which is threaded into the socket 57 formed in the valve plug 23, a gasket 58 being interposed between the head of the plug 56, and the end 90 of the valve 23. Positioned in the passage 55 is a valve stem 59 carrying the valve plug 60 which is normally held by the spring 61 in open position.

Leading into the compartment 39' is a pipe 95 62 which is attached to an air pump 63 operated by the engine 64 of the boat to force air into the compartment 39'. When this air enters the compartment 39', the valve plug 60 will be moved from its seat, permitting the 100 passage of air through the passages 51 and 52 into the compartment 40'. The spring 48 tends to normally retain the piston 46 in its outwardly pressed position, and formed in the socket 45 is a groove 64 communicating 105 with a plurality of radially extending openings 65 so that moisture which may accumulate in the socket 45 will not interfere with the operation of the piston 46, this moisture being projected downwardly through the 110 openings 65. Should any accident happen to the compartment 39' so as to reduce the pressure therein, the disc 46 would be forced to move inwardly of the socket 45 against the compression of the spring 48, bringing the 115 end of the stem 47 into engagement with the end of the passage 53 formed in the block 54, and thus closing communication between the compartment 40 and the compartment 39'. Should an accident happen to the compartment 40' so that the pressure in the compartment 40' would be suddenly lessened below the pressure in the compartment 39', the heavier pressure in the compartment 39' would force the valve plug 60 against its 120 seat so as to seal communication between the compartments 39' and 40'.

In this manner there is provided a safety check valve for each of the compartments whereby they may be in communication with 125

each other until the pressure of one is considerably reduced below the pressure of the other, when a closing of the valves will take effect. This is particularly desirable when the air forced by the pump 63 is delivered to the compartments of the drums in sufficient quantities to raise the air to a high degree of compression.

Positioned midway of the boat in a vertically extending member having the side walls 66 and 67. Journalled in, and positioned between, these side walls 67 and 66 are gears 68 and 69, the gear 69 being connected to, and driven by, the shaft 70 of the motor 64. The gear 68 meshes with the gear 69. Carried on the face of the gear 69 is a similar gear 71 travelling over which is a silent chain 72 which passes over the gear 73, this gear 73 being fixedly mounted upon the shaft 74 which is journalled in the bearing 75 supported by the side wall 67. Fixedly mounted upon the shaft 74 is a hub 76, to which is secured the offset portion of the disc 77, said disc being offset at its center and provided at its edge with a flange 78 which is secured to the drum section 41. A nut 79 is threaded on the shaft 74 and covered with a suitable cap 80 which serves to retain in position the gasket 81. As shown in Fig. 1, one of these drums is positioned at one side of the longitudinal medial line of the boat, and the other drum is positioned at the other side. The shaft 74 is extended and connected to the drum 82 in the same manner as it is connected to the forward drum, the drum 82 being journalled at its forward end similarly to the journalling of the section 41. At the rear end projecting downwardly from the casting 32 is a bearing 84 in which the bolt 83 is secured, the construction of the rear end of this drum being the same as the construction of the forward section 39. The gear 68 carries on its face a gear 85, around which rides the silent chain 86 travelling on the gear 87 which is fixed on a shaft to drive the drum 88 in the same manner that the drum at the opposite side thereof is driven. The rear drum section 89 is also driven the same as the rear drum section 82, the mounting and supporting of this drum being as already described.

Co-operating with the walls 66 and 67 is a base 90 which extends around the gearing so as to seal this gearing mechanism from the water. A piping 91 is connected to a suitable lubricating pump 92 for forcing lubricant into the bearings and keeping these parts well lubricated. Mounted on the periphery of each of the drums is a spirally extended blade or fin projecting radially outwardly therefrom. As shown clearly in Fig. 2, the blade travels around the drum in a spiral arrangement but is deflected into various planes. The portion 93 of the blade lies in a different plane than does the portion 94,

or the intermediate portion 95. However, the arrangement is such that a perpendicular line to the blade at any one point will project outwardly from the outer edge of the adjacent blade, and this feature is effected by the particular formation and twisting of the blade on the drum. By forming the blade in this manner as it enters the water while rotating for the purposes of propelling the boat, the maximum amount of pressure is delivered in a propelling manner to the boat as the blade serves to twist its way through the water with the minimum resistance, while at the same time delivering a thrust axially of the drum, but delivering this thrust at a slight angle thereto, so as to clear the edge of the next succeeding blade projection. This movement of the drums effects a propelling of the vehicle with a minimum amount of disturbance of the water. The drums are intended to be of such size as to retain the boat structure well above the water line, under ordinary conditions the water line extending to about a horizontal plane projected through the axis of the drums.

By arranging the drums at opposite sides of the boat and extending them throughout practically the entire length of the boat, a maximum propelling force is delivered to the boat, this propelling force, on account of the peculiar arrangement of the blade on the drums, serving to drive the boat through the water at a maximum speed with an easy floating effect, thus relieving the boat of the jars and strains to which the ordinary boat is subjected. By having the air cushions at the bow and the stern of the boat, the rocking is prevented, as previously mentioned.

The container 22 may be used for additional buoyancy, this container being filled with air for buoying purposes or filled with water or other material to be used as a ballast.

Each of the drums is provided with a man-hole 96 whereby the drum may be entered for repairs, cleaning or other necessary work.

In Fig. 8 and Fig. 11 I have shown a modified form in which the drum 97 is formed with a single compartment 98 and provided at its periphery with a plurality of separated cleats 99 having the outwardly projecting blade forming portion 101, these cleats being arranged in an irregular spiral around the periphery of the drum 97. As shown in Fig. 8, these drums are each formed with a single compartment, and a plurality of drums 102 may be joined end to end, a bearing 103 being mounted in one of the compartments through which a bolt 104 may be projected, said bolt engaging in the bearing 105 and in a bore formed in the bracket 106 which may be suitably secured to the deck of the boat. The driving of these drums will be effected similarly to the driving arrangement already mentioned.

In Fig. 9 I have shown the drum 108 pro-

70

105

110

115

120

125

130

vided with a plurality of partitions 109 and 110, so that the drum is divided into a large number of non-communicating compartments, thus reinforcing the drum and providing separate buoying compartments, each of which may serve its function independently of the other.

In Fig. 10 I have shown a modified form in which the drum 111 is provided at its opposite ends with discs 112 and 113 in which is secured the ends of stay rods 114 carrying the blade 115 which is projected around the drum in an irregular spiral, a belt 116 serving, on account of its connection with the pulley 117 mounted on the bolt 118 which extends through the supporting bearing 119, to rotate the stay rods 111.

In Fig. 12 I have shown a pair of drums 120 and 121 secured together by the frame 20 work 122 in which is positioned a differential mechanism 123 driven by the shaft 124 of the engine motor 125. This differential may be used where it is desired to drive the boat under conditions requiring a sharp turn so that the drums at one side of the vessel may be employed for propelling purposes independently of the other. This is desirable in some instances, although generally the rudder 126 will be sufficient for ordinary purposes.

If desired, the drums may be filled with gas to give greater buoyancy, if for any reason such buoyancy is desired, although under ordinary conditions, the inflation of the drums with air has proven sufficient.

A boat constructed in this manner is one which affords a rigid structure and which may be subjected to great strains without in any manner interfering with the life of the boat, or its efficiency in operation. Furthermore, by raising the boat out of the water and using only those portions which serve to engage the water for the purpose of propelling, a maximum efficiency is attained in the driving of the boat through the water.

It is preferred that the various parts from which the boat is to be made be fabricated from metal so that a fire proof and non-sinkable boat is thus provided.

While I have illustrated and described the preferred form of my invention, I do not wish to limit myself to the precise details of structure shown, but desire to avail myself of such variations and modifications as come within the scope of the appended claims.

Having thus described my invention what I claim as new and desire to secure by Letters Patent is:

1. In a boat of the class described, a plurality of rotatable buoyant drums; partition forming members in said drums for dividing the same into a plurality of compartments; a valve mounted in each of said partitions for establishing communication between said compartments, said valves being constructed

and arranged to close upon reduction of pressure of one compartment excessively relatively to the pressure in the other compartment; and means for rotating said drums.

2. In a boat, a plurality of rotatable buoyant members; partition members in said buoyant members for dividing the same into a plurality of compartments; a valve for communicating said compartments and automatically closing said communication upon rapid lowering of the pressure in one of said compartments below the pressure in the other.

3. In a boat, a plurality of buoyant members; a plurality of partition members in each of said buoyant members for dividing the same into a plurality of compartments; a valve in said partition members for establishing communication between said compartment members, said valve being automatically operated for closing said communication upon excessive rapid lowering of the pressure in one compartment below the pressure in an adjoining compartment.

4. In a boat, a plurality of buoyant members; a plurality of partition members in each of said buoyant members for dividing the same into a plurality of compartments; valves in said partition members for establishing communication between said compartment members, said valve being automatically operated for closing said communication upon excessive rapid lowering of the pressure in one compartment below the pressure in an adjoining compartment; and means for forcing air into said compartments under pressure.

In testimony whereof I have signed the foregoing specification.

CHALON E. BRIDWELL.
